FIG. 2

FIG. 1

INVENTOR.
WILLIAM LOEVEN
BY Benjamin, Roodhouse & Lundy
ATTORNEYS.

UNITED STATES PATENT OFFICE.

WILLIAM LOEVEN, OF CHICAGO, ILLINOIS.

WRENCH.

1,338,313.

Specification of Letters Patent. Patented Apr. 27, 1920.

Application filed October 10, 1919. Serial No. 329,699.

To all whom it may concern:

Be it known that I, WILLIAM LOEVEN, a citizen of the United States, residing at Chicago, in the county of Cook and State of Illinois, have invented new and useful Improvements in Wrenches, of which the following is a specification.

My prevent invention relates to improvements in jam-wrenches, or what are generally known as pipe-wrenches, which are adapted to grip round objects, although they may be used for nuts and other objects having parallel opposite faces.

The objects of my present invention are the provision of such a structure which is simple in construction and may be economically manufactured, and which affords simple facilities for its quick and ready adjustment to the size of articles upon which it is to be employed. Further objects will be apparent to others after an understanding of my invention is had, and I prefer to accomplish these divers objects in substantially the manner hereinafter disclosed.

In the drawings:

Figure 1 represents an article embodying my invention showing the same in side view, a portion thereof being broken away to more clearly show the assembly of the handle or lever with the element carrying the opposite jaw.

Fig. 2 is a view of the structure shown in Fig. 1 at right angles to and from the top thereof.

As will be seen in the drawings, the handle element 1 consists of a piece of bar-metal of, preferably, rectangular cross-section the corners or edges 2 at one end whereof are, preferably, rounded or beveled to provide a better gripping portion or handle. The opposite end of the handle element is cut in an arc shape and serrated, as indicated at 3, for the better gripping of round objects. It will be observed that the arc above referred to is struck from a center eccentric to and above the longitudinal axis of handle element 1 for the purpose to be hereinafter referred to.

Between the handle portion and the arc-shaped end of the handle element is a slot 4 one of the edges whereof is waved to provide a plurality of pockets 5 which are separated by teeth 6. The member to assemble with the handle element, preferably, comprises a piece stamped from sheet metal of suitable thickness. This blank or stamping is bent

centrally upon itself to provide parallel arms 7 adapted to extend upon opposite sides of the handle element. A pin or pintle 8 passes between the respective arms and through slot 4 in the handle element. The arms 7 are provided at their ends beyond pin 8 with lateral extensions 9 which are bent laterally toward each other, which, together with the pintle, limit the latitude of movement of the handle element. The portion of the blank at and adjacent the central bend is laterally extended to provide the preferably inclined jaw 10, and for the purpose of re-inforcing this jaw a suitably hardened block 11 may be secured 70 therein by rivets 12, or otherwise.

My invention operates as follows:—The pipe or other object to be engaged is brought between jaw 10 and the adjacent edges of arms 7. The handle element is then advanced until the serrated arc-shaped end 3 engages the face of the pipe or other article. The handle element is then moved so that pintle 8 will seat in pocket 5 opposite to said pintle when the arc-shaped end is in 80 engagement with the pipe or other element, and the handle is then pulled in an upward direction or in a direction tending to cause it to aline with arms 7. As pintle 8 is eccentric to the center of arc 3 this movement 85 will cause the serrations to bite into the object operated upon thereby preventing the latter from moving with respect to the wrench.

From the foregoing description, taken in 90 connection with the drawing, it will be apparent that I have provided an extremely simple wrench of dependable action, which is economical to manufacture and quick and easy in operation.

Having described my invention, what I claim as new and desire to secure by Letters Patent is:

1. A wrench comprising a handle element having a slot intermediate its ends one edge whereof is provided with a plurality of pockets and one end of which handle element is provided with an eccentrically centered arc-shaped serrated surface, a member coacting with said handle element consisting of a blank folded to form parallel arms between which said handle element is disposed, a pintle extending between said arms and through the slot in said handle element, a laterally extended jaw having an inclined face produced adjacent the bend of said blank, and lateral projections extend-

ing from the opposite ends of said arms adapted to limit the relative movement of said handle element.

2. A wrench comprising a handle element having a slot intermediate its ends one edge whereof is provided with a plurality of pockets and one end of which handle element is provided with an eccentrically centered arc-shaped serrated surface, a member coacting with said handle element consisting of a blank folded to form parallel arms between which said handle element is disposed, a pintle extending between said arms and through the slot in said handle

element, a laterally extended jaw having an 15 inclined face produced adjacent the bend of said blank, lateral projections extending from the opposite ends of said arms adapted to limit the relative movement of said handle element, and a block fitted into the end of 20 said blank and secured to said jaw.

Signed at Chicago, county of Cook and State of Illinois, this 7th day of October, 1919.

WILLIAM LOEVEN.
